COUNTING DEVICE

Norbert L. Enrick and Gaston G. Fornes, Charlottesville, Va., assignors to Institute of Textile Technology, Charlottesville, Va., a corporation of Virginia

Filed Oct. 15, 1959, Ser. No. 846,733

6 Claims. (Cl. 48—68)

This invention relates to counting devices for indicating and recording the number of times certain events occur and, more particularly, to a manually operated counter constructed simply of a barrel, a spindle, and a detent device fixed with respect to the spindle to hold the barrel in various selected angular positions.

Simple counting devices of the type disclosed and claimed herein are normally used to record the number of occurrences of some particular event or happening when the maximum number of occurrences to be counted is relatively limited. Counters of this sort may be employed, for example, on spinning machines, looms, and other weaving apparatus to count and record the number of various faults which take place during a given period of operation, so that a record is always available of the condition of the equipment. For this and many other applications, a counting device should be capable of quick and easy actuation by the operator so that the events may be recorded with speed and accuracy. The device should also be readily attachable to the particular apparatus with which it is associated. Furthermore, since a large total number of events need not be recorded, it is important that the counting device be of uncomplicated and inexpensive design.

It is the primary purpose of the present invention to provide a counting device which possesses these various advantages. The new device includes a barrel having a bore extending axially therethrough. At least a portion of the barrel is defined exteriorly by a plurality of similar surfaces adjoining one another about the circumference of the barrel. Markings of different indicia denote these respective surfaces. A spindle is positioned freely within the bore and an end portion of the spindle projects from the bore to provide means for mounting the device. Retaining means are included for holding the barrel on the spindle when the device is mounted. A fixed resilient detent strip is adapted to extend laterally outwardly from the spindle to bear resiliently against the barrel. Hence, the barrel may be manually rotated about the spindle to a plurality of selected angular positions and releasably held in such positions by the detent strip.

That portion of the barrel defined exteriorly by the adjoining similar surfaces serves several purposes in the operation of this new counting device. In one embodiment of the invention, it provides a series of cam-like surfaces against which an outer end portion of the detent strip is adapted to bear resiliently to hold the barrel in its selected positions. It also provides areas on which numbers or other indicia may be formed to distinguish the various angular positions of the barrel. Moreover, it forms a knob-like element which the operator can easily grip to turn the barrel to its selected position. In a preferred form, the barrel may be cut from rod stock of octagonal cross section so that this exterior portion comprises eight uniformly shaped flat surfaces extending longitudinally from one end of the barrel and equiangularly adjoining one another about the circumference of the barrel. Also, ordinary flat strip and round rod stock may be used to form the detent strip and spindle respectively, so that the entire device may be formed by a few ordinary machining steps.

A preferred embodiment of the invention is described hereinbelow with reference to the accompanying drawing, wherein

2

FIG. 1 is an exploded elevation of the new counting device and a fragmentary section of a frame to which it is to be attached;

FIG. 2 is a plan view of a detent strip of the counting device of FIG. 1;

FIG. 3 is an elevation partly broken away and in section of several of the counting device of FIG. 1 mounted on the frame of a loom; and

FIG. 4 is an end view of the apparatus of FIG. 3.

Referring first to FIGS. 1 and 2, a portion of a frame 10 is shown formed with an internally threaded hole 11. The frame 10 may be part of a loom, for example, and it should be visible and within the reach of the operator. The counting device includes a spindle 12 which may be formed from ordinary round rod stock. At one end of the spindle 12 is a head portion 13 provided with a slot 14 on its outer face for turning the spindle with a screwdriver or the like. Extending from the head portion 13 of the spindle is a cylindrical central portion 15 and on the end of the central portion is a longitudinally projecting externally threaded end portion 17. The end portion 17 is of smaller diameter than the central portion 15 and its external threads correspond to the internal threads in the hole 11 in the frame 10. Thus, the threaded end portion 17 provides means for mounting the spindle on the frame.

Indicated generally by the numeral 18 is a barrel which is formed with a bore 19 extending axially therethrough. At the end of the bore remote from the frame 10 a counterbore 20 is formed which is substantially equal in depth to the head portion 13 of the spindle 12. The barrel 18 is defined externally by a plurality of uniformly shaped flat surfaces 21 extending longitudinally from one end thereof and equiangularly adjoining one another about the circumference of the barrel. In the embodiment shown in FIG. 1, three of the surfaces 21 are visible and there are eight in total, so that the barrel 18 may be conveniently cut from octagonal rod stock. Markings 23 of different indicia, such as consecutive numbers, are formed on and denote the various flat surfaces 21. The exterior surface of the barrel is also defined by a conically tapered surface 25 converging longitudinally from the flat surfaces 21 to the end of the barrel. At the end of the barrel opposite the conical surface 25 is a small circular land 26 formed concentrically about the adjacent end of the bore 19.

The longitudinal dimension of the bore 19 from the base of the counterbore 20 to the face of the land 26 is just slightly smaller than the longitudinal dimension of the central portion 15 of the spindle 12. Also, the diameters of the bore 19 and counterbore 20 are just slightly larger than the diameter of the central portion 15 and head portion 13 respectively of the spindle. Hence, the spindle may extend freely through the barrel 18 with the head portion 13 recessed substantially flush within the counterbore 20.

As shown in FIGS. 1 and 2, the counting device also includes a detent strip 28 of resilient material, such as spring steel. The detent strip is formed with a round hole 29 adjacent one end thereof adapted to loosely receive the threaded end portion 17 of the spindle. The hole 29 is considerably smaller in diameter, however, than the central portion 15 of the spindle. At the outer end of the detent strip 28 is a bent-over portion 31 which is spaced from the center of the hole 29 a distance somewhat less than the shortest distance from the center line of the barrel 18 to one of the flat surfaces 21.

In assembling the new counting device, the spindle 12 is fitted into the barrel 18 so that the threaded end portion 17 projects from one end of the bore 19. The head portion 13 of the spindle is then recessed within the counterbore 20 as described. The threaded end portion

17 of the spindle is fitted through the hole 29 in the detent strip 28 and the detent strip is then brought up flat against the face of the land 26 on the barrel. This causes the bent-over end portion 31 of the detent strip to bear resiliently against one of the flat surfaces 21 on the barrel 18. The spindle 12 is then screwed into the hole 11 in the frame 10 by means of the slot 14 until the detent strip is held fixed between the central portion 15 of the spindle and the surface of the frame 10. Since the central portion 15 is longer than the bore 19 of the barrel, the barrel remains freely mounted about the spindle.

To operate the device, the barrel 18 is manually gripped about the flat surfaces 21 and turned on the spindle. The bent-over end portion 31 of the detent strip is thereby caused to ride over the successive flat surfaces 21 in 15 resilient contact therewith. When the bent-over end portion 31 of the detent strip reaches the flat surface denoted by the desired number or other indicia 23, the barrel is left held in that position by the detent strip. Alternatively, some form of arrow or mark may be formed on the surface of the frame 10 to register with and denote the desired indicia on one of the flat surfaces 21.

In FIGS. 3 and 4, a particular application of the new counting device is shown. On part of a frame 35 of a loom or other machine, an upright member 36 is fastened by means of screws 37. The upright member 36 includes a flange portion 39 which strengthens it and provides a flat plane for the formation of a plurality of internally threaded holes 40 similar to the hole 11 in the embodiment of FIGS. 1 and 2. In each of the internally threaded holes 40 a new counting device 41 is mounted.

As described in reference to FIGS. 1 and 2, each counting device 41 comprises a spindle 42, a barrel 43 and a detent strip 44. On the face of the upright member 36 in clear view of the operator of the loom, are formed certain titles 46 which denote the respective counting devices. Each title designates a particular type of fault which is likely to occur in the operation of the loom. If only a very few of these faults occur during operation, the loom will not be shut down, but if the number of occurrences increases to a certain critical level then loom is stopped so that the difficulty may be corrected.

The new counters, therefore, are used to record the number of various faults which occur. The operator simply rotates the barrel 43 of the appropriate counting device one eighth of a turn to indicate when a particular fault occurs so that the detent strip 44 holds the barrel in its new angular position and records the number of such occurrences. The looms are periodically inspected to make note of the number of faults which had occurred during the previous elapsed period. If the number is critically high the loom is shut down, the faults are corrected, and the counters are returned to a zero reading.

We claim:

1. A counting device comprising a barrel having a bore extending axially therethrough, at least a portion of said barrel being defined exteriorly by a plurality of similar substantially flat surfaces adjoining one another about the circumference of the barrel, markings of different indicia denoting the respective surfaces, a spindle positioned freely within said bore such that said barrel is rotatably mounted thereon, an end portion of said spindle projecting from said bore and providing means for mounting said device, retaining means for holding said barrel on said spindle when said device is mounted, and a resilient detent strip fixed with respect to and extending laterally outwardly from said spindle when said device is mounted, said detent strip having an outer end portion bearing resiliently against the respective flat surfaces on said barrel in a selected angular position thereof, whereby said barrel may be manually rotated about said spindle to a plurality of selected angular positions and releasably held in such positions by said detent strip.

2. A counting device comprising a barrel having a

bore extending axially therethrough, at least a portion of said barrel being defined exteriorly by a plurality of substantially flat surfaces equiangularly adjoining one another about the circumference of the barrel, markings of different indicia denoting the respective flat surfaces, a spindle positioned freely within said bore such that said barrel is rotatably mounted thereon, an end portion of said spindle projecting from one end of said bore and providing means for mounting said device, retaining means for holding said barrel on said spindle when said device is mounted, and a detent device comprising a strip of resilient material formed with a hole adjacent one end for receiving the projecting end portion of said spindle and a bent-over portion at the other end bearing resiliently against the respective flat surfaces of said barrel in a selected angular position thereof, said strip being fixed relative to said spindle and extending laterally outwardly therefrom when said device is mounted, whereby said barrel may be rotated about said spindle to a plurality of selected angular positions and held releasably in such positions by the bent-over portion of said detent strip.

3. A counting device comprising a barrel having a bore extending axially therethrough, at least a portion of said barrel being defined exteriorly by a plurality of substantially flat and uniformly shaped surfaces equiangularly adjoining one another about the circumference of the barrel, markings of different indicia on said barrel denoting the respective flat surfaces, a spindle positioned freely within said bore such that said barrel is rotatably mounted thereon, a threaded portion on one end of said spindle projecting from one end of said bore for mounting said device, a cylindrical head portion on the other end of said spindle substantially recessed in a counterbore at the other end of said bore for retaining said barrel on said spindle when said device is mounted, and a detent device comprising a strip of resilient material formed with a hole adjacent one end for receiving the threaded end portion of said spindle and a bent-over portion at the other end bearing resiliently against the respective flat surfaces of said barrel in a selected angular position thereof, said strip being fixed relative to said spindle and extending laterally outwardly therefrom when said device is mounted, whereby said barrel may be rotated about said spindle to a plurality of selected angular positions and held releasably in such positions by the bent-over portion of said detent strip.

4. A counting device adapted to be mounted on a frame comprising a barrel having a bore extending axially therethrough, a portion of said barrel being defined exteriorly by a plurality of substantially flat and uniformly shaped surfaces equiangularly adjoining one another about the circumference of the barrel, markings of different indicia on said barrel denoting the respective flat surfaces, a spindle positioned freely within said bore and including a cylindrical central portion such that said barrel is rotatably mounted thereon, a narrower threaded end portion extending from said central portion and projecting from one end of the bore for attachment to said frame, and a cylindrical head portion at the opposite end of said central portion recessed substantially flush within a counterbore at the other end of said bore for retaining said barrel on said spindle, and a resilient detent strip formed with a hole adjacent one end for receiving the threaded end portion of said spindle and a bent-over portion at the other end bearing resiliently against the respective flat surfaces of said barrel in a selected angular position thereof, said strip being held fixed between the central portion of said spindle and said frame when said spindle is threaded to said frame, whereby said barrel may be rotated about said spindle to a plurality of selected angular positions and held releasably in such position by the bent-over portion of said detent strip.

5. A counting device adapted to be mounted on a frame comprising a barrel having a bore extending axially

therethrough, said barrel being defined exteriorly by a plurality of uniformly shaped flat surfaces extending longitudinally from one end of the barrel and equiangularly adjoining one another about the circumference of the barrel and also by a conically tapered surface converging longitudinally from said flat surfaces to the other end of the barrel, markings of different indicia on said barrel denoting the respective flat surfaces, a spindle positioned freely within said bore and including a cylindrical central portion such that said barrel is rotatably mounted thereon, a narrower threaded end portion extending from said central portion and projecting from the end of the bore adjacent said flat surfaces for attachment to said frame, and a cylindrical head portion at the opposite end of said central portion recessed substantially flush within a counterbore at the end of said bore adjacent said tapered surface for retaining said barrel on said spindle, means on the outer face of said head portion for turning said spindle into threaded attachment with said frame, and a resilient detent strip extending laterally outwardly from said spindle, said strip being formed with a hole adjacent one end for receiving the threaded end portion of said spindle and a bent-over portion at the other end bearing resiliently against the respective flat surfaces of said barrel in a selected angular position thereof, said strip being held fixed between the central portion of said spindle and said frame when said spindle is threaded to said frame, whereby said barrel may be rotated about said spindle to a plurality of selected angular positions and held releasably in such position by the bent-over portion of said detent strip.
